UNITED STATES PATENT OFFICE.

FRANK A. PILCHER, OF BINGHAMTON, NEW YORK, ASSIGNOR OF ONE-THIRD TO MYRON C. BEMAN AND ONE-THIRD TO FRANK BEMAN, BOTH OF BINGHAMTON, NEW YORK.

AUTOMATIC MUSICAL INSTRUMENT.

1,224,783.

Specification of Letters Patent.

Patented May 1, 1917.

Application filed May 10, 1912. Serial No. 696,536.

To all whom it may concern:

Be it known that I, FRANK A. PILCHER, a citizen of the United States, residing at Binghamton, in the county of Broome and State of New York, have invented certain new and useful Improvements in Automatic Musical Instruments, of which the following is a specification, reference being had therein to the accompanying drawing.

10 My invention has to do with automatically controlled pipe organs of the commonly known type, and is directed particularly to the securement of adaptability for the rendition of music from music sheets arranged in various ways, and this without the use of cumbersome devices and connections, and without the usually attendant weak and unreliable constructions subject at times to variations due to atmospheric or climatic 15 conditions. While having the particular relation and direction stated however, it will be apparent upon an understanding of my invention that the same may be used either as a whole or in part in connection with 20 musical instruments of other types, with attendant advantages additional to those just recited.

As is well known, the pipe organ is one of the most difficult of instruments to control, 25 owing to the great number of registers employed and to the correspondingly great number of stop control devices of the stop action requisite to effect the desired changes from one register to another, to effect the 30 combinations between the same, and the general government of the individual registers. In pneumatically controlled organs of the type to which the present invention relates, it has previously been customary to make 35 use of a very cumbersome control system comprising pneumatic primaries, pneumatic secondaries and other devices of this nature controlled in their action from a trackerboard and perforated music sheet to effect 40 the orderly operation of the various sounding devices of the registers and the stop action. According to my invention the pneumatic primaries, pneumatic secondaries and other devices of this nature which have 45 formerly been used are eliminated, and the sounding devices, stop action and other accessories are controlled electrically.

The adaptability and flexibility of control secured through the use of my invention result from a particular relation and combina-

tion of the elemental controls and operating devices of the several registers and the stop action with a peculiarly devised trackerboard which itself enters into and forms a part of my invention. This trackerboard 60 is provided with two parallel rows of control connections, the respective connections of the rows being staggered with respect to each other. In other words the control connections of one of said rows are positioned 65 on lines of traverse passing substantially midway between the connections of the other of said rows. The connections in the two rows are preferably equal in number each to each and of substantially the same dimensions. They are normally all in operation 70 at the same time. The control devices of one register are operatively associated with one of said parallel rows of trackerboard control connections, while the control devices of another one or two registers are associated with the other of said rows. The coöperating perforated music sheet is prepared by interpolating the control perforations for the one register controlled through 75 one row between those of the register or registers controlled through the other row.

By the provision of suitable well-known types of switches in electrical controlling circuits extending from the control devices 80 associated with the trackerboard to the operating devices directly controlling the stop action and sounding devices, complete shifts may be made of the registers and stop action from control through one group of control 85 connections to another. Thus the registers may be shifted to control from the upper set of control connections instead of the lower, and the stop action shifted to be controlled by the lower. Thus also the two 90 registers may be interchanged between left and right of either the upper or the lower row of control connections without interfering with the stop action, and so also the two registers may be operated, one from a 95 part of each row of trackerboard control connections, and the stop action may be operated at the same time either from one or from both rows. The number of combinations is great, and it will be readily seen 100 that the provision of such a means makes it possible to render music from sheets on which it is arranged in many different ways. Thus although sheets may be at hand, one of which has music for the accompaniment 105 110

arranged on the left of the sheet, and the solo on the right, and the other of which has the solo on the left and the accompaniment on the right, etc., both of these may be individually rendered without difficulty by a simple transposition of the control of the registers from one side of the trackerboard to the other. The particular arrangement of the control perforations in two rows positioned as specified makes the control shift easy and operation certain.

Other advantages will appear after a full understanding of my invention.

In the accompanying drawings I have shown one embodiment of my invention. Of the drawings

Figure 1 is a diagrammatic view of the instrument, certain of the relay control and operating elements being shown in section, 20 and the trackerboard being also shown in section.

Fig. 2 is a front elevation of the trackerboard showing the upper portion of the co-operating perforated music sheet.

Fig. 3 is a front elevation of the same trackerboard showing the modified control arrangement.

Fig. 4 is a sectional view of a modified form of trip stop action box of the type shown generally in Fig. 1.

Referring first to Figs 1 and 2 it may be seen that in this system I make use of a trackerboard 10 having two parallel rows of staggered control connections or perforations, substantially coextensive with each other. The connections in one of the rows 11 are positioned on lines of traverse passing midway between the connections 12 of the other row. In other words, the connections in each of the two rows are similarly spaced and are of substantially the same size, and the connections of one row are positioned opposite the bridges 13 of the other row in the line of travel. Preferably the connections do not overlap, but are of equal or less extent than the bridges between the connections. The spacing in any one row may be that of the perforations of the standard note sheets.

50 A note sheet 14 of the usual form co-operates with this trackerboard. It is passed over the trackerboard from top to bottom, being drawn from the upper spool 15 by the rotation of the winding roll 16. The perforations in this sheet however are differently positioned from those in the usual sheets in that control-perforations for the upper row trackerboard connections 11 are interpolated between those co-operating with the lower row of trackerboard connections 12.

Control connection tubes 17 connecting with the upper row of connections 11 at one end extend to the individual pneumato-electric actions 18 through which the stop action is controlled. As indicated by the legends in

Fig. 2 control-connecting tubes 19 (Fig. 1) extend from the left hand portion of the lower row of trackerboard connections 12 to the accompaniment controlling pneumato-electric actions 20, while connecting tubes 21 70 extend from the right hand portion of the row of perforations 12 to the solo pneumato-electric actions 22. Thus the stop action is controlled entirely in this embodiment from the top row 11 of trackerboard connections 75 while the accompaniment and solo pneumato-electric actions are controlled each from a different portion of the lower row 12 of trackerboard connections. Thus the accompaniment and solo parts are arranged on opposite sides of the center of the perforated music sheet 14 while the stop action part of the music is interpolated between the accompaniment and solo parts. Instead of arranging the control connections of the stop 85 action in the upper row, I may arrange the control connections of an instrument register in the upper row, and the stop action at one end in either or both rows as designated by legends in Fig. 3. Herein are the 90 principal features of my invention.

Proceeding now further, it will be seen how well these features lend themselves to the elimination of complications in the remainder of the control system, and in the 95 attainment of adaptability and flexibility.

The control pneumatics 18, 20 and 22 of the stop action and the two registers respectively are identically alike, and the pneumatic 18 only, therefore need be described. 100 It comprises a box 23 over the bottom of which extends a diaphragm 24 which forms with the bottom of the box a puff pneumatic. A control connection 17 communicates with this pneumatic. A duct 25 connects the interior of the pneumatic with the upper part of the box 23 above the diaphragm 24, while suction tube 26 connects the upper part of the box with any suitable suction pump or bellows. The operation is as usual. 110

Extending into the upper space of the box 23 from an outer terminal 27 and overlying the diaphragm 24 is a contact spring 28 adapted to be moved by diaphragm 24 into contact with the fixed terminal 29 115 which extends through the top of the box 23 and into proximity to the end of the contact spring 28. An operating arm 30 is connected with the top of the diaphragm 24, and the spring 28 rests upon its outer end, pressing the diaphragm 24 downwardly. A stop 31 limits this downward movement. Whenever the pneumatic is actuated upon the opening of the corresponding connection of the row 11 to atmosphere, 120 an electrical contact is made between the spring 28 and the terminal 29.

By this contact a circuit is completed from battery B over conductor 32 and conductor 33 to and including magnet 34 125

and back by conductor 35 to the battery. The magnet 34 is the control magnet of one of the operating pneumatics of the stop action. This pneumatic is constructed in general in a manner essentially similar to that disclosed in my Patent No. 952,546, March 22, 1910. It comprises generally a box 36 open to the wind blast from a pressure pump or bellows as usual. Within the box and mounted on shelf 37 is power pneumatic 38 carrying at its outer end a depending pivoted operating arm 39 which co-operates with the oscillating valve control member 40. This member 40 is pivoted to a post 41 and carries at each end a valve 42 adapted respectively to close the open ends of ducts 43 and 44 which lead from the interior of the box 36 to the pneumatic devices for operating the stop action. In connection with the duct 44 is shown one of these devices 45 which may be any known type or form and which may control the stop action in any suitable manner.

When the pneumatic 38 is collapsed, assuming that the lever 40 is in the position shown in which one valve 42 closes the duct 44 while the duct 43 is opened, the arm 39 passes on the left hand side of the central pyramidal shifting projection 46 and operates the member 40 to close the duct 43 and open duct 44 which was previously closed. Upon a succeeding operation of the pneumatic 38, the member 39 passes to the opposite side of the shifting projection 46 and shifts the member 40 back to its previous position. Thus by this operation that duct 43 or 44 which is closed is always opened by an action of the pneumatic, and that which was opened is closed. The detailed construction of these parts and their operation, including that of the lever 47, are given in full in my prior Patent No. 952,546 issued March 22, 1910, and need not be repeated here.

The control of the pneumatic 38 is effected through magnet 34. The magnet 34 is mounted in an extension 48 from the box 36. It is a double pole magnet and straddles the aperture 49 in a valve plate 50 on which it is mounted and which is fitted over the valve chamber 51 formed in the bottom of the extension 48. Extending through the bottom of the valve chamber is a vent tube 52 the upper end of which is faced to form a valve seat. A valve 53 is placed in the valve chamber between the valve seats of the members 50 and 52. Preferably it is in the form of a disk of magnetic material covered with suitable material adapting it to effect tight closures of the valve openings 49 and 54 although it may be constructed in other ways. The valve chamber 51 communicates with the pneumatic 38 by a duct 55. Thus normally when the magnet 34 is deenergized, air un-

der pressure passes through the chamber 51 and duct 55 and maintains the pneumatic 38 distended. When however the magnet is energized by the closing of this circuit by one of the pneumato-electric actions 18, the valve armature 53 is attracted, closing the valve chamber from the wind chest and venting the pneumatic 38 through the valve 52, thus collapsing the pneumatic and operating the stop action, through the oscillation of the valved carrying member 40.

The control pneumato-electric actions 20 and 22 connect respectively with the operating pneumatics 56 and 57 of separate registers as for instance of the accompaniment and solo parts. The circuits of these operating pneumatics are closed by the control pneumato-electric actions 20 and 22 in a manner entirely similar to that in which the circuit of the magnet 34 of the stop action is closed by a control pneumato-electric action 18. The operating pneumatics 56, 57 of all of the registers are essentially the same and consequently only one need be described.

The operating pneumatics for the sounding devices comprise boxes 58 open to the wind blast from the pressure chamber, and containing pneumatics 59 constituted by one side wall of the box 58 and diaphragm 60 pivoted at its lower end to the wall of the box and flexibly connected at its upper end as is usual and as more fully described in my prior Patent No. 815,978, March 27, 1906. The pipes 61 are connected with the interior of the box through ducts 63 the inner end of which terminates in an inclined valve seat 64 controlled by a valve 65 pivoted at its upper end and spring pressed to its closed position by spring 66. The lower end of the valve is connected to the side 60 of the pneumatic by a flexible cord or other such means 67. Whenever the pneumatic 59 is collapsed the valve is opened and air from the wind-blast admitted to operate the pipe 61 or other sounding device 61.

The pneumatic 59 is electrically controlled by a magnet 68 which operates a disk valve 69 through a construction and in a manner entirely similar to that shown in connection with the stop action previously described. 70 is the valve opening in the plate 71 on which the magnet is mounted, 72 is the valve chamber, 73 is the vent tube and 74 is the duct communicating with the interior of the pneumatic. Thus it is apparent that direct electrical action is secured without the use of pneumatic primaries, pneumatic secondaries, etc. The result is the extremely light and efficient construction, and rapid and accurate operation.

Having now an understanding of the invention its adaptability will be manifest. By the simple use of proper electrical switches which may be manually operated

or which may be pneumatically or electrically operated by devices under the control of the perforations in the trackerboard, the control of the registers may be interchangeably had from different parts of the trackerboard without in any wise impairing the efficiency of action. In Fig. 1 I have shown a double-pole double-throw, reversing switch 75 which, it is to be understood is one element of a gang switch adapted to effect such an interchange between the operating devices 56 of the accompaniment register and the devices 57 of the solo register, thus interchanging them between the right and left portions of the lower row of perforations 12 of the trackerboard. I have shown this switch diagrammatically, with the usual bridging contacts or blades indicated in dotted lines but its structural form is well known in the art as are also the pneumatic and electrical devices by which it may be automatically operated. In fact control pneumatics 18 and the trip stop-action of the type shown may be used to throw the switch 75. In a similar manner and by the use of entirely similar means, the two registers shown may be interchanged between the top and bottom rows of perforations 11 and 12 of the trackerboard as indicated in Fig. 3. Furthermore still other registers which are normally idle may be substituted for any one of those shown.

The great advantages of this invention are at once obvious. The connections of the trackerboard may be so placed that either the upper row 11 or the lower row 12 may be used with standard single register music, or with music written for several registers, no matter what the record arrangements of the sheet, whether the record of one register is right and the other left with the stop action interpolated between the two as shown, or whether the records of the two registers are interpolated, and the stop action is at one side of the sheet, and no matter on which side the record of a given register is written—by the use of proper switches, the control system may be adapted to suit. And if convenience dictates that the record of a register shall sometimes be written on one side and sometimes on the other of the same sheet, the shift may be made in the control system by the simple inclusion of a control perforation adapted automatically to effect the shift as indicated. Such a control perforation and the method of use are described in my prior patent hereinabove referred to.

Having thus described my invention what I claim and desire to secure by Letters Patent is:

1. An automatic musical instrument comprising a stop action and player action for a given register, a trackerboard having two rows of staggered control connections, con-

trol devices for the stop action operatively connected to the control connections of one of said rows, and control devices for the player action operatively connected with the control connections of the other of said rows.

2. An automatic musical instrument comprising a stop action and sets of player actions for a plurality of registers, a trackerboard having two rows of staggered control connections, control devices for the stop action operatively connected to the control connections of one of said rows, and a set of control devices for each of said sets of player actions operatively connected each to the control connections of the other row, one set to the right portion and the other to the left portion of the row.

3. An automatic musical instrument comprising a stop action and sets of player actions for a plurality of registers, a trackerboard having two rows of staggered control connections, control devices for the stop action operatively connected to the control connections of one of said rows, and a set of control devices for each of said sets of player actions each operatively connected to control connections of the other row, one set to the right portion and the other to the left portion of the row, and means for interchanging the control of said set of player actions between the right and left portions of said row.

4. An automatic musical instrument comprising: sounding devices arranged in a plurality of registers; means for actuating said sounding devices individually; means for controlling each register of sounding devices as a whole; electromagnets one for actuating each of the last mentioned controlling means; a branch circuit for each of said magnets; a source of current for all of said circuits; a pneumatically operated circuit closer in each branch; a single manual switch in each branch, to open and close the same and thereby cut out or cut in at will the corresponding controlling device; a gang reversing switch connected in a plurality of said branches, to shift and reverse at will the connection of a plurality of registers of the sounding devices with the circuit closers; a trackerboard; and a note sheet with means to cause the same to travel over said trackerboard and means to control the circuit closers therethrough.

5. An automatic musical instrument comprising sounding devices divided into a plurality of registers, means for actuating individually the sounding devices in each register, a trackerboard and means to operate said actuating means from the trackerboard, a stop device for controlling all the sounding devices in each register, an electromagnet actuating each controlling device, a branch circuit for each electromagnet, a

source of current for all of said circuits, a pneumatically operated circuit closer for each branch, and a gang reversing switch connected in said branch circuits to shift or 5 reverse at will the control connections between the several registers and the several circuit closers.

In testimony whereof I affix my signature in presence of two witnesses.
